UNITED STATES PATENT OFFICE.

WILLIAM H. RUGH, OF COLFAX, OHIO.

FENCE-WIRE STRETCHER.

SPECIFICATION forming part of Letters Patent No. 242,049, dated May 24, 1881.

Application filed March 30, 1881. (No model.)

To all whom it may concern:

Be it known that I, WILLIAM HENRY RUGH, a citizen of the United States, residing at Colfax, in the county of Fairfield and State of Ohio, have invented certain new and useful Improvements in Devices for Stretching Fence-Wire; and I do hereby declare that the following is a full, clear, and exact description of the same, reference being had to the annexed drawings, making a part of this specification, and to the letters and figures of reference marked thereon.

Figure 1 of the drawings is a side elevation of my invention; Fig. 2, a plan view of the frame and rotary straining-bar connected to a fence-post, and Fig. 3 is a detail view of the cam-lever and plate for holding the wire.

This invention has reference to certain new and useful improvements in portable devices for tightening fence, telegraph, and other wires; and it consists in the construction of the several parts, as illustrated in the drawings, and hereinafter described.

In the drawings, A represents an angular frame, of metal, cast with the arms a, to form bearings for a rotary straining-bar, B, and the arm b to receive a set-screw, C. This frame A embraces the two angular sides of the fence-post D, and is held thereto by the set-screw C. To one end of the bar B is rigidly connected a ratchet-wheel, e, for engaging with a pawl, d, pivoted to the side of the angular frame A, which prevents the bar from turning back or in the wrong direction when the wire is being tightened.

The bar B may have a suitable handle or crank, e, for turning it, and suitable spur-gearing may be attached to the bar to facilitate operating it.

To the outer end of the bar B is connected

one end of a chain, f, and to the opposite end of said chain is secured a plate, E, to which is pivoted a cam-lever, g, said plate having a hook, h, for convenient attachment of the chain f.

Between the face of the cam-lever g and upper surface of the plate E is securely held the fence-wire i, which is tightened by drawing the cam-lever and plate in the direction of the angular frame A, this being accomplished by turning the bar B in the proper direction to wind up the chain f.

The frame A, which is one of the important features of my invention, is cast from a single piece of metal with the arms a and the arm b, which not only simplifies its construction and reduces the cost in the manufacture of this class of devices, but renders it easily attached to the fence-post and as readily removed. As the frame only embraces two sides of the post the set-screw C holds it firmly in place.

Having now fully described my invention, what I claim as new, and desire to secure by Letters Patent, is—

In a device for tightening or stretching fence and other wire, the angular frame A, formed with arms a a b, set-screw C, pawl d, and shaft B, having its bearings in the arms a a, and the ratchet-wheel e, connected to said shaft, in combination with the chain f, having connected thereto the plate E and the cam-lever g, substantially as and for the purpose set forth.

In testimony that I claim the above I have hereunto subscribed my name in the presence of two witnesses.

WILLIAM HENRY RUGH.
